CLAIM

The ornamental design for landing gear for an aerial vehicle, as shown and described.

DESCRIPTION

FIG. 1 is a rear, top, and left side perspective view of a folded landing gear for an aerial vehicle;

FIG. 2 is a front, bottom, and right side perspective view of the folded landing gear for an aerial vehicle;

FIG. 3 is a rear elevation view of the folded landing gear for an aerial vehicle.

FIG. 4 is a front elevation view of the folded landing gear for an aerial vehicle.

FIG. 5 is a left side elevational view of the folded landing gear for an aerial vehicle;

FIG. 6 is a right side elevational view of the folded landing gear for an aerial vehicle;

FIG. 7 is a top plan view of the folded landing gear for an aerial vehicle;

FIG. 8 is a bottom plan view of the folded landing gear for an aerial vehicle.

FIG. 9 is a rear, top and left side perspective view of the open landing gear for an aerial vehicle;

FIG. 10 is a front, bottom, and right side perspective view of the open landing gear for an aerial vehicle;

FIG. 11 is a rear elevation view of the open landing gear for an aerial vehicle;

FIG. 12 is a front elevation view of the open landing gear for an aerial vehicle;

FIG. 13 is a left side elevational view of the open landing gear for an aerial vehicle;

FIG. 14 is a right side elevational view of the open landing gear for an aerial vehicle;

FIG. 15 is a top plan view of the open landing gear for an aerial vehicle; and,

FIG. 16 is a bottom plan view of the open landing gear for an aerial vehicle.

The broken lines in the drawings showing portions of the landing gear are included for the purpose of illustrating environmental structure and form no part of the claimed design.
